WELL DEVICE

Herbert C. Otis, Dallas, Tex.

Application December 3, 1946, Serial No. 368,343

7 Claims. (Cl. 166—2)

This invention relates to new and useful improvements in well devices.

One object of the invention is to provide an improved device for controlling the flow of fluids in wells.

An important object of the invention is to provide an improved well packer, which is adapted to be positioned within the well bore by means of the well tubing to seal off the producing formation therebelow, and having incorporated therein a removable flow controlling device for controlling the passage of well fluids from the producing formation below the packer to the bore of the well above the packer.

Another object of the invention is to provide an improved well device for use in wells having more than one producing formation and which includes an improved packer which may be positioned within the bore of the well to separate the producing formations therein outside the tubing, and having a flow controlling device removably mounted therein which may be utilized to control the flow of well fluids from one of the formations to the other, whereby the flow of fluids in either direction past the packer may be controlled, and the fluids from one formation may be utilized to aid in producing the other formation.

A further object of the invention is to provide an improved device of the character described which may be detachably connected to the well tubing, whereby the device may be lowered into the well bore, locked therein, and withdrawn from the well by means of the well tubing; and which is so constructed that it may also be removed from the well by retrieving tools lowered into the well and operated by means of a flexible cable or wire line, after the tubing above the device has been disconnected therefrom and removed from the well.

Another object of the invention is to provide an improved well device of the character described wherein the flow controlling means may be removed from the device to afford substantially full opening of the bore of the tubing, whereby the well may be cleaned, or bottom hole pressure bombs, temperature gauges or other instruments may be lowered past the packer.

Still another object of the invention is to provide an improved packer having expansible anchoring means and a sealing element which are adapted to be positively actuated by manipulation of the well tubing, the packer having a releasable coupling means operable by the well tubing whereby the anchoring means may be held

in non-anchoring position and the sealing element may remain in a non-sealing position until the tubing is manipulated to release said coupling means and to positively actuate the anchoring means and the sealing element.

A still further object of the invention is to provide a packer of the character just described wherein the means for expanding the anchoring means and the sealing element are both moved to inoperative position and held in such position by means of a unitary coupling element, so that a single operation will release both the sealing means and the anchoring means for actuation or will render them both ineffective.

15 A particular object of the invention is to provide an improved packer having a well fluid bypass provided therein between the well tubing and the packer to facilitate lowering the packer through well liquids and to permit circulation of fluids past the packer, which by-pass passage is closed off upon distortion of the sealing element of the packer to sealing position; said sealing element itself closing off the annular space between the wall of the well bore and the well 20 tubing to close the by-pass.

25 Additional objects and advantages of the invention will be apparent from a reading of the following description of a device constructed in accordance with the invention, and reference to 30 the accompanying drawings, wherein:

Figure 1 is a view, partly in elevation and partly in section, of the upper portion of a device constructed in accordance with the invention, and showing the same being lowered into a well bore.

35 Figure 2 is a continuation of Figure 1, showing the lower portion of the device.

Figure 3 is a view, partly in elevation and partly in section, of the upper portion of the device showing the same in anchored sealing position 40 in the well bore and with the removable flow controlling device in position therein.

Figure 4 is a continuation of Figure 3, showing the lower portion of the device in anchored sealing position.

45 Figure 5 is a horizontal cross-sectional view taken on the line 5—5 of Figure 1.

Figure 6 is a horizontal cross-sectional view taken on the line 6—6 of Figure 4.

Figure 7 is a view, partly in elevation and partly in section, of a modified form of the invention, showing the device being lowered into a well bore.

50 Figure 8 is a view similar to Figure 7, showing the device in anchored sealing position within the well, and

Figure 9 is a horizontal cross-sectional view taken on the line 9-9 of Figure 7.

In the drawings the numeral 10 designates an elongate tubular mandrel having an axial bore 11 extending therethrough. The upper outer portion of the mandrel is substantially cylindrical and a slip supporting carrier or sleeve 12 is slidably mounted thereon. An external annular flange 13 is provided at the upper end of the slip carrier and has its under side inclined to form an undercut shoulder 14. The lower portion of the slip carrier or sleeve is enlarged and the lower end of this enlarged portion has a plurality of equally spaced T-shaped slots 15 formed therein (see Fig. 4). The upper ends of gripping elements 16, which upper ends are also T-shaped, are slidably inserted within these slots. A retaining band 17, which fits within an annular groove 18 formed in the periphery of the slip carrier, surrounds the carrier and prevents outward displacement of the gripping elements from the slots. The gripping elements are, therefore, suspended from the slip carrier and are movable radially and longitudinally with relation to the mandrel 10.

For limiting the longitudinal movement of the slip carrier on the mandrel, the latter is formed with an external flange 19, preferably integral therewith, near the lower end of the cylindrical portion of the mandrel. As is clearly shown in Fig. 1, this flange is slotted to permit the gripping elements 16 to extend therethrough. A confining ring 20 fits within an annular groove formed in the flange and confines the gripping elements within the slots in the flange, whereby the gripping elements are retained in close proximity to the mandrel.

The lower portion of the mandrel, below the flange 19, is inclined or flared outwardly to form a slip expanding section 21. Each gripping element 16 includes an arcuate slip 22 at its lower end and the inner surface of each slip engages and rides upon the inclined surface 21 of the mandrel. The outer surface of each slip is formed with serrated gripping teeth 23 which are adapted to engage the inner wall of a well casing or pipe C to prevent upward displacement or movement of the assembly, as will be explained. When the slips 22 are at the upper end of the inclined portion 21 (Fig. 1) and immediately below the flange 19, further upward movement of the slips and slip carrier is prevented and said slips are retracted and out of engagement with the casing wall; however, movement of the mandrel upwardly with relation to the slips causes radial outward movement of the slips to the position shown in Fig. 4, whereby the slips engage the casing wall, and in such position further upward displacement of the mandrel is prevented.

Immediately below the flared slip expanding portion 21, the mandrel is formed with external screw threads, and an annular retaining collar or sleeve 24 is threaded thereon, as clearly shown in Figs. 1 and 4. The collar extends below the lower end of the mandrel and is held in position thereon by means of a set screw 25 which extends through said collar and engages the mandrel to prevent rotation of the collar on the mandrel.

The lower end of the bore of the mandrel is enlarged and is provided with internal screw threads 26. An elongate flexible packing sleeve or element 27, made of fabric-reinforced rubber, "Neoprene," or other suitable material, has its

upper end molded around and affixed to the lower end of a packing supporting ring 28. The ring 28 is provided with a plurality of external annular flanges 29, by means of which longitudinal displacement of the packing sleeve from the ring is inhibited. The upper end of the ring is formed with external screw threads and is threaded into the lower end of the bore of the mandrel 10, whereby said packing sleeve is secured to the lower end of the mandrel. The upper end of the outer surface of the packing sleeve is reduced slightly in diameter and is tightly engaged by the retaining collar 24, whereby the upper end of said packing sleeve is held securely to the lower end of the mandrel, confined between the collar and the ring 28. Below the collar and ring, the sleeve is free to be expanded into sealing engagement with the wall of the casing C, as will be explained.

The bore of the packing sleeve and the bore of the supporting ring 28 are substantially equal to the bore 11 of the mandrel 10 and form a downward continuation thereof. The lower end of the bore of the packing sleeve is bevelled at 30.

The external diameter of the sleeve is less than the bore of the well casing and the lower outer end portion of the sleeve is formed with an annular depending skirt 31, which is provided with an inwardly bevelled edge so the sleeve will pass freely through the casing without hanging or catching on projections or irregularities therein.

An elongate tubular coupling member 32 has its lower portion 33 slidable into the upper portion of the bore 11 of the mandrel. The upper portion of the coupling member is enlarged to a diameter substantially equal to the external diameter of the cylindrical upper portion of the mandrel, whereby a downwardly facing external shoulder 34 is formed on said coupling member.

The coupling member is releasably connected to the mandrel 10 by means of an outwardly extending radial lug 35, formed on the lower portion 33 of the member, which lug extends through and co-acts with a J-shaped slot 36 formed in the upper portion of the mandrel. A superposed, corresponding, co-extending J-shaped slot 37 is formed in the upper portion of the slip carrier 12 and the lug 35 also extends into and co-acts with this J-slot. The arrangement of the J-slots 36 and 37 and the lug 35 is such that when the shoulder 34 on the coupling member engages the upper end of the mandrel, as shown in Fig. 1, the lug is in the lower portion of the J-slots and may be rotated into the lateral or horizontal portion of said J-slots.

With the lug in the lateral portion of the J-slots, the coupling member is connected to and held against longitudinal movement within the mandrel 10 by means of the engagement of the lug with the J-slot 36, and the slip carrier 12 is held in its uppermost position by means of the engagement of the lug with the J-slot 37. In this position the slips 22 are held in a retracted position at the upper end of the inclined section 21 of the mandrel.

The coupling member has an axial bore 38 extending therethrough and the lower end of said bore is provided with internal screw threads. The upper end of a spacer nipple or pipe 39 is threaded into the lower end of the bore of the coupling member and extends downwardly through the bore of the mandrel 10 and the packing sleeve 27 to project a short distance below said packing sleeve. It is pointed out that the diameter of the spacer nipple 39 is less than the

bore of the mandrel and packing sleeve, whereby an annular flow passage or space 11a is provided therebetween. A plurality of spaced radial bypass ports or openings 10a are provided in the wall of the mandrel, and are shown just above the flange 18 (see Figs. 1 and 6) though they may be at other suitable locations therein. Thus well fluids entering the flow passage 11a from below the packing sleeve may flow upwardly through said passage and the ports 10a to the bore of 10 the well above the packer.

An elongate packing expanding member 48 having an axial bore 41 is connected to the lower end of the spacer nipple 39 and a section of the well tubing T is connected to the lower end of 15 said expanding member. The upper portion of the member 48 is cylindrical and is slidable into the bore of the packing sleeve and the supporting ring 28. An outwardly flared or inclined section 42 is formed near the lower end of the member 48 for expanding the packing sleeve 27, as will be explained. Immediately below the inclined section 42 the member 48 is enlarged to form an upwardly directed annular shoulder 43, below which the member is tapered inwardly toward its lower end.

When the lug 35 on the coupling member 32 is engaged in the lateral portion of the J-slot 36 in the mandrel, the packing expanding member is spaced below the lower end of the packing sleeve, as is clearly shown in Figs. 1 and 2. When the well tubing T, which is connected to the upper end of the coupling member and extends upwardly therefrom to the well surface, is rotated, the coupling member is rotated therewith. Thus, the lug 35 may be moved into alignment with the vertical portion of the J-slots 36 and 37 and, when the lug is within this portion of the slots, an upward movement of the coupling member with relation to the mandrel 18 and slip carrier 12 is possible.

In order to frictionally restrain the slip carrier and mandrel against rotation and free longitudinal movement within the casing C, to permit the lug 35 to be moved into and out of the J-slots, a plurality of friction shoes 45 are mounted within equally spaced recesses 46 formed in the periphery of the enlarged portion of the slip carrier, as clearly shown in Fig. 1. The friction shoes are urged outwardly into engagement with the wall of the casing by coiled springs 47 confined between the shoes and the bottom of the recesses. The friction shoes are held against displacement from the recesses by means of the retaining band 48 at their lower ends and at their upper ends are held by a similar band 49, which fits within an annular groove formed in the upper end of the enlarged portion of the slip carrier. Since the gripping elements 16, suspended from the slip carrier, extend through the slots in the mandrel flange 18, it will be seen that the mandrel, as well as the slip carrier, will be held against rotation. Of course, other forms of friction holding means may be employed if desired.

When the coupling member 32 is disconnected from the mandrel and moved upwardly with relation thereto, the packing expanding member 48 will be lifted. When this is done, the upper cylindrical portion of the expanding member enters the bore of the packing sleeve 27 and the inclined section 42 engages the bevelled lower end of the sleeve. Continued upward movement of the expanding member then moves the mandrel 18, to which the packing sleeve is secured, upwardly with relation to the slip carrier and the slips 22.

whereupon the inclined slip expanding section 21 moves the slips outwardly into gripping engagement with the well casing C and further upward movement of the mandrel is prevented. Obviously, further upward movement of the expanding member and the inclined section 42 thereon will force the packing sleeve upwardly and outwardly into sealing engagement with the wall of the well casing. Since the packing sleeve also engages the exterior of the expanding member, it is readily apparent that the flow passage 11a between the spacer nipple 39 and the mandrel 18 is also closed off by said packing sleeve. Thus, the single packing sleeve 27 serves both to close off the by-pass passage through the packer and to seal off the well bore outside the tubing.

With the device in the position illustrated in Figs. 3 and 4, the well fluids entering the bore of the well below the packer will be directed into flow inlets (not shown) at the lower end of the well tubing T and will flow upwardly through said tubing and through the expanding member 48, spacer nipple 39 and coupling member 32, which form a part of the tubing string.

For controlling the flow of the well fluids through the packer, a flow controlling device F is provided in the coupling member 32. While many suitable forms of the device may be used, it is preferable that a device similar to that illustrated in my United States Letters Patent No. 2,144,850, dated January 24, 1939, be used.

As is clearly shown in Fig. 3, the lower portion of the bore 38 of the coupling member is reduced to form a housing 49 having an elongate annular locking recess 50 near its upper end. The flow control device F, which is adapted to be inserted into the housing 49 and locked therein, consists of an elongate carrier 51 having a cylindrical neck 52 at its upper end extending upwardly from a flared or inclined shank 53, which latter constitutes an expanding element. The shank extends upwardly from a cylindrical head 54, from which a reduced stem 55 depends. The head is slightly less in diameter than the bore of the housing 49 so as to freely slide thereinto.

A dog supporting collar 56 has a sliding fit on the neck 52 and is provided with an annular undercut flange 57 at its upper end. A plurality of locking dogs 58 having T-shaped upper ends 59 are suspended from T-shaped slots 59 formed in the lower end of the collar, similar to the slots 15 in the slip carrier 12. A retaining collar 60 is mounted on the upper end of the neck 52. An annular stop flange 61 surrounds the base of the neck 52, and the locking dogs extend through slots in this flange. The flange is provided with an annular inclined shoulder which is adapted to engage the inclined seat at the upper end of the housing 49 to limit downward movement of the carrier 51 within the housing.

The locking dogs 58 have bosses 61 at their lower ends which are arranged to engage the annular shoulder 50a formed at the upper end of the locking recess 50 when said dogs are expanded by the flared shank 53, upon which they are slidable (Fig. 3.) When the dogs are at the upper end of the flared shank they are retracted and may enter and be withdrawn from the housing 49, but when they are at the lower end of the shank they are expanded and will engage within the locking recess to prevent displacement of the carrier upwardly out of the housing.

On the reduced stem 55 inverted sealing cups 62 are mounted and held in spaced relationship by spacer rings 63. The cups are made of fab-

ric impregnated with rubber, or other suitable composition, and are slightly smaller in diameter than the bore of the housing, whereby they may readily enter the same. Well pressure fluid entering the bore of the housing expands the cups to sealing engagement with the wall of the bore of the housing. While the cups are illustrated in position to seal off fluid pressures from below the carrier, it is obvious that the cups may be mounted to seal off pressure fluids from above, or from both above and below, if desired. A tubular valve cage 64 is screw-threaded onto the lower end of the stem 55 and confines the cups and spacer rings between its upper end and the lower end of the head 54. A changeable flow controlling bean or orifice member 65 is screw-threaded into the lower end of the bore of the carrier 51, and the flow of well fluids through the device F is controlled by the size of the orifice in this bean. Obviously, well fluids flowing up the well tubing will expand the cups 62 into sealing engagement with the bore of the housing 49 and thus the well fluids will be directed through the bean into the bore of the carrier, from which they may flow upwardly within the tubing. If desired, the bean 65 may be replaced with a suitable valve member (not shown) for completely shutting off the flow through the bore of the carrier 51, and thus flow through the bore of the packer may be shut off.

Radial ports 10 are provided in the upper portion of the coupling member 32, whereby the well fluids which have flowed through the flow controlling device F may pass outwardly from the bore of the well tubing into the annular space between the tubing and casing, where they may be allowed to accumulate until pumped or otherwise produced from the well. The removal of such accumulated well fluids from above the packer has no appreciable effect on the flow of the well fluids from the producing formation below the packer, since the quantity and rate of flow of such fluids through the packer from the formation is controlled by the orifice in the bean 65. The ports 10 may, of course, be omitted and the well fluids flowed on directly up the tubing to the well surface.

In use, the assembly is connected in the well tubing string T, as shown in Figs. 1 and 2, with the lug 35 on the coupling member in the lateral portion of the J-slots 36 and 37, whereby the slips 22 are held retracted and the packing expanding member 40 is spaced below the packing sleeve 27 so that the sleeve is in an undistorted position.

With the parts in this position, the device is lowered into the well casing. Should the device be lowered into and through well liquids, such liquids will pass around the packing sleeve and through the flow passage 11a, between the sleeve and the spacer nipple 39, and through the ports 10a to the bore of the well above the device.

When the desired depth at which the device is to be set has been reached, the tubing is rotated to rotate the lug 35 into alignment with the vertical portion of the J-slots. With the friction shoes 45 holding the slip carrier and gripping elements 16 against free movement, the tubing is lifted and the packing expanding member 40 engages the lower end of the packing sleeve 27 to move the sleeve, together with the mandrel 10, upwardly with relation to the slips 22. As the mandrel is moved upwardly, the inclined section 26 thereof expands the slips into gripping engagement with the wall of the casing C, and further upward movement of the mandrel is prevented. A con-

tinued upward pull on the tubing moves the packing expanding member 40 upwardly within the packing sleeve, whereby the inclined section 26 of the member 40 distorts said packing sleeve upwardly and outwardly into sealing engagement with the well casing. At the same time, the flow passage 11a is closed by the engagement of the sleeve with the exterior of the expanding member, as has been explained, and the bore of the well outside the tubing string T is completely closed off. The tubing is ordinarily held taut to positively maintain the slips in gripping engagement and to maintain the packing sleeve in sealing engagement with the well casing.

After the device has been anchored in the casing, the usual well surface connections (not shown) are installed.

The flow controlling device F is then lowered through the well tubing to position within the housing 49 by means of a suitable running device (not shown), which may be the same as that illustrated in my above mentioned Letters Patent No. 2,144,850. The running device would be connected to the flow device at the retaining collar 66 at the upper end thereof, and the flow device lowered to and locked within the housing 49, after which the running device is detached from the device F and removed from the well. If desired, the flow device F may be locked in position within the housing 49 at the well surface and lowered into the well with the packer assembly.

The well surface controls (not shown) may then be opened and the well fluids from the producing formation below the packer permitted to flow upwardly through the bean 65 in the flow device, either to the bore of the well above the packer through the ports 10 or directly up the tubing to the well surface, if such ports are omitted. Obviously, any well fluid pressure below the packer which is acting upwardly against the packing sleeve 27 will tend to expand both the packing sleeve and the slips 22 into a tighter engagement with the well casing, though both are held in expanded position by the upward pull on the tubing T.

Thus, it will be seen that well fluids will flow upwardly through the packer and the flow controlling device F and thence outwardly through the ports 10 into the bore of the well above the packer. The well bore above the packer and flow controlling device forms a reservoir which is mechanically separated from the producing formation by such packer and flow controlling device assembly, and well fluids may be allowed to accumulate in this reservoir until they are removed therefrom by pumping or by some other means. The daily allowable production of the well may thus flow into the reservoir, separated from the producing formation, from which reservoir the allowable quantity of fluids may be removed by pumping at an efficient rate without affecting the flow from the producing formation into the reservoir.

This practice is particularly desirable in wells wherein the allowable daily oil production is less than may be pumped efficiently at slow rates, and in wells wherein operation of pumps at normal rates causes "coning" or increased production of water from the producing formation. As a result of limiting rates of flow through the combination by means of the bean 65, withdrawal from the producing formation sufficient to cause "coning" or increased water production is prevented; and, by providing the reservoir above the assembly, oil may be allowed to accumulate

in such reservoir until there is a sufficient quantity for pumping at efficient rates. Therefore, the assembly provides for substantially uniform flow of well fluids from the producing formation into the reservoir, and permits withdrawal of accumulated fluids from the reservoir, at any desired rate and in any suitable manner, without such withdrawal materially affecting the flow from the producing formation.

Should it be desired to change the size of the orifice in the bean 65, the flow device F may be removed from the housing 49 by means of a suitable retrieving tool (not shown) lowered into the well tubing on a small steel line. A retrieving tool similar to that illustrated in my United States Letters Patent No. 1,898,261, dated February 21, 1933, is especially suitable for such use, though others may be used. The retrieving tool will engage the under cut flange 51 at the upper end of the collar 56 on the flow device, and by moving the carrier 58 downwardly with relation to the dogs 59, permit the dogs to retract and the device to be lifted from the housing to the well surface. The bean 65 may be replaced by another bean having the desired size orifice therethrough, or a valve assembly (not shown) may be mounted within the valve cage 64, and the flow device again lowered into the housing and locked therein. Thus, the rate of flow through the packer may be controlled by means of the changeable bean 65, or flow may be cut off by use of a valve assembly instead of the bean. Production of well fluids is, therefore, positively controlled by use of the packer with the flow device therein.

In case it should be desired to run bottom hole pressure bombs, temperature gauges, or other instruments requiring a substantially full opening through the tubing, the flow device may be removed from the housing 49 as has been explained, and such tools may then be lowered past the packer to the bottom of the well tubing.

To remove the packer from the well or to change its position therein, the well tubing T is lowered until the coupling member 32 enters the upper end of the mandrel and the shoulder 34 on said member engages the upper end of the mandrel. In this position, the packing expanding member 40 has been lowered out of the packing sleeve 27, whereby said sleeve may return to its original shape out of sealing engagement with the wall of the casing. The fluid passage 11a is also opened and well fluids may pass through said passage and the ports 10a to the bore of the well above the packer whereby the fluid pressures across the packer are equalized.

At this point, with the by-pass passage 11a open, fluid may be circulated through the well in the usual manner, down through the tubing and upwardly past the packer between the tubing and casing, to clean out sand or other matter which may have accumulated above the packer, whereby removal of the packer is facilitated.

The weight of the tubing string is then applied to the mandrel 10, through the engagement of the shoulder 34 with the upper end of said mandrel, to move the same downwardly with relation to the slips 22, whereby said slips are moved to retracted position at the upper end of the inclined section 21 of the mandrel. The lug 35 is then rotated into the lateral portion of the J-slots 36 and 37, to lock the parts in the position shown in Figs. 1 and 2, and the assembly

may be raised or lowered within the well bore to a new position, or removed therefrom.

In some installations it may be desired or necessary to provide for removing the well tubing T above the packer from the well independently of the packer, and to later remove the packer itself by means of retrieving tools lowered into the well and operated therein by means of a flexible wire line or cable (not shown). In such

10 case, the tubing T will be connected to the upper end of the coupling member 32 by means of left hand screw threads, or other suitable "back-off" connecting means, whereby said tubing may be disconnected from said coupling member and removed from the well bore, leaving the packer positioned therein.

A retrieving tool similar to that illustrated in my Letters Patent No. 1,898,261, or other suitable tools, may then be lowered into the well 20 on a steel line or cable to engage or catch under the flange 13 on the upper end of the slip carrier. The coupling member 32 is driven downwardly to move the mandrel 10 downwardly with relation to the slips and thus release said slips from gripping engagement with the well casing. After the slips have been released, the retrieving tool is lifted, and, since it is engaged with the slip carrier, the slips are held in their retracted position and the packer may be lifted to the 25 surface.

It will be readily seen that, if desired, the packer may be positioned between two separate producing formations within the well bore, to control the flow from one to the other. One of

30 the formations may contain well fluids under high pressure, while the other formation may produce more desirable well fluids at a lower pressure, which will not ordinarily flow such fluids to the surface. Thus, if the device is po-

35 sitioned between the formations, the high pressure fluids may be flowed, at rates and quantities controlled by means of the bean 65, into the low pressure formation to increase the pressure therein and provide a "drive" to aid in producing 40 the well fluids from such low pressure formation.

If the formation containing the fluids under the higher pressure is above the packer, such fluids will enter through the ports 10 and flow

45 downwardly through the flow controlling device 50 F and through the packer to the low pressure formation below the packer. The rate of flow from the upper high pressure formation to the lower low pressure formation is controlled by the ori-

55 ficed bean 65 in the same manner as if the flow were upwardly through the packer; and, by changing the orifice in the bean, desired rates and quantities of flow from the one formation to the other may be obtained. The higher pres-

60 sure fluid will enter the formation containing the fluid under the lower pressure and provide energy, in the form of higher pressure fluid, for flowing such low pressure fluids from the low pressure formation into other adjacent wells and thence to the surface. The well surface controls

65 of the well in which the assembly is positioned would, of course, be closed during such operation. Obviously, the flow may be directed from a high pressure formation below the assembly to a low pressure formation thereabove for the same purpose.

A slightly modified form of the invention is shown in Figures 7 to 9. In this form, the by-pass passage 11a is omitted. The spacer nipple 138 of this form is shorter than the nipple 39

of the previous form, whereby the upper cylindrical portion of the packing expanding member 40 is positioned within the bore of the packing sleeve 21 when the expanding member is in its lowermost position, as is shown in Fig. 7. It is noted, however, that the packing sleeve is not expanded until the inclined section 42 is moved upwardly therein.

Since there is no flow passage 11a, the bypass ports 10a of the first form are also omitted.

The upper portion of the coupling member 132 is shorter than the upper section of the member 32, although this is of no particular importance, except to shorten the assembly.

The slip carrier 112 of the modified form of the device is slightly different from the slip carrier of the first form. Instead of having the elongated enlarged lower portion shown in the first form, the slip carrier 112 is formed with a short enlarged lower portion or flange 77 at its lower end and with an annular external flange 75 at its mid-portion. The under side of the flange 75 is formed with an annular groove 75a therein, into which the upper ends of the friction shoes 45 are adapted to fit, as shown in Fig. 7. For spacing the shoes 45 around the periphery of the slip carrier 112, sectors of an annular ring 76 are welded or otherwise secured within the groove 75a to maintain the shoes in spaced relationship. The lower ends of the friction shoes are confined by the ring 77 within spaced recesses 146 formed in the short annular flange 77 at the lower end of the slip carrier.

In other respects and details the modified form of the device is the same as the form first described, and is operated in the same manner.

In both forms the single lug 35 engages and co-acts with coextensive corresponding J-slots 36 and 37 formed in the mandrel and slip carrier, whereby the gripping elements 16 may be held in a retracted non-gripping position and, at the same time, the packing expanding member 40 is held in inactive non-distorting position relative to the packing sleeve 21. By releasing the unitary coupling provided by the engagement of the lug with the J-slots, the gripping elements may be expanded to anchoring engagement and the packing sleeve distorted to sealing position; a single continued upward movement of the tubing effecting actuation of both the gripping elements and the packing sleeve.

Likewise, an improved device is provided for positively controlling the flow of well fluids from a producing formation to another formation, or through the device to the well bore thereabove, from which they may be produced to the well surface as desired without materially affecting the flow through the device from the producing formation.

The above description of the invention is explanatory only, and changes in details of the constructions illustrated may be made by those skilled in the art, within the scope of the appended claims, without departing from the spirit of the invention.

What I claim and desire to secure by Letters Patent is:

1. A well packer including, a tubular mandrel having means for anchoring it within a well; a tubular packing element carried by the mandrel; a well tubing movable longitudinally through said mandrel and packing element; means for releasably coupling said tubing to said mandrel, whereby said mandrel may be lowered into the

well and anchored in sealing position therein by manipulation of the tubing; said packing element being spaced from said tubing to form a fluid by-pass passage between the well tubing and the packing element, whereby fluids may flow therethrough past the packer; and means operable by the tubing for distorting the packing element into sealing position within the well bore, said packing element also closing the fluid by-pass passage upon such distortion.

2. A well packer including, a tubular mandrel; movable gripping means for anchoring the mandrel within a well bore; a tubular packing element carried by the mandrel; a tubular coupling member having means for connecting it to a well tubing and slideable within the mandrel and packing element, said coupling member providing means for releasably coupling the mandrel to the well tubing; the packing element being spaced from the coupling member to provide a fluid by-pass passage therebetween, whereby fluids may flow therethrough past the packer; and means for distorting the packing element into sealing engagement with the well bore, said packing element engaging the coupling member and closing off the fluid by-pass passage upon such distortion, whereby the well is sealed off outside the tubing by said packing element.

3. A well device including, a packer having a tubular mandrel; gripping means expansible on said mandrel for anchoring the same within a well bore; an elongate tubular packing element carried by the mandrel; a coupling member having means for connecting it in a well tubing string and slideable within said mandrel and packing element for releasably coupling said mandrel to said tubing; a fluid by-pass passage between the coupling member and the packing element whereby fluids may flow therethrough past the packer; means for distorting said packing element into sealing engagement with the well bore, said packing element also closing off the fluid by-pass passage upon such distortion, whereby the well is sealed off outside the coupling member by said packing element and the flowing well fluids are directed through the coupling member; means establishing communication of the well fluids flowing through the coupling member with the bore of the well above the packer; and a well fluid flow controlling member removably mounted within the coupling member for controlling the flow of well fluids therethrough past the packer to the bore of the well thereabove.

4. A well packer including, a tubular mandrel having a cylindrical upper portion and a downwardly and outwardly flared lower portion; a carrier slideable on the cylindrical section of the mandrel; gripping elements suspended from the carrier and slideable on the flared portion of the mandrel, whereby said gripping elements may be expanded into anchoring engagement with a well casing; a coupling member slideable within the mandrel and having an external lug thereon arranged to co-act with coextensive corresponding J-shaped slots formed in the upper ends of the carrier and the mandrel; an elongate tubular packing sleeve carried by the lower end of the mandrel and surrounding the lower portion of the coupling member; and a packing distorting member carried by the lower end of the coupling member and movable longitudinally therewith to engage and distort the packing sleeve into sealing engagement with the well casing; the J-slots and lug being so arranged that when the

lug is in the short lateral portion of the J-slots the coupling member is held against longitudinal movement through the mandrel whereby the packing expanding member is held out of distorting engagement with the packing sleeve, and at the same time the gripping elements are held in unexpanded non-gripping position, whereby the packer may be moved through the well casing; said lug being movable out of the short lateral portion of the J-slots to permit the coupling member to be moved upwardly, whereby the packing expanding member is moved upwardly to distort the packing sleeve into sealing position and the gripping elements are expanded to anchor the packer within the well casing.

5. A well packer including, a tubular mandrel having means for anchoring it within a well bore; an elongate tubular packing sleeve mounted on the lower end of said mandrel and having its lower portion distortable into sealing engagement with the wall of the well bore; an elongate tubular coupling member slidable longitudinally within the mandrel and having a packing sleeve distorting member at its lower end below the packing sleeve; and a fluid by-pass passage between the coupling member and the packing sleeve whereby fluids may flow therethrough past the assembly; said coupling member being arranged to be connected in a well tubing string to form a part thereof and to be movable thereby, whereby upward movement of the tubing will lift the coupling member and the packing distorting member carried thereby to cause said distorting member to engage and distort the packing sleeve into sealing engagement with the wall of the well bore, the engagement of the distorting member with the packing sleeve also closing off the by-pass passage whereby flowing well fluids are directed through the coupling member.

6. A well packer including, a tubular mandrel having a cylindrical upper portion and a downwardly and outwardly flared lower portion; a carrier slidable on the cylindrical section of the mandrel; gripping elements suspended from the carrier and slidable on the flared portion of the mandrel, whereby said gripping elements may be expanded into anchoring engagement with a well casing; a coupling member slidable within

the mandrel and having an external lug thereon arranged to co-act with coextensive corresponding J-shaped slots formed in the upper ends of the carrier and the mandrel; an elongate tubular packing sleeve carried by the lower end of the mandrel and surrounding the lower portion of the coupling member; a packing distorting member carried by the lower end of the coupling member and movable longitudinally therewith to engage and distort the packing sleeve into sealing engagement with the well casing; the J-slots and lug being so arranged that when the lug is in the short lateral portion of the J-slots the coupling member is held against longitudinal movement through the mandrel whereby the packing expanding member is held out of distorting engagement with the packing sleeve, and at the same time the gripping elements are held in unexpanded non-gripping position, whereby the packer may be moved through the well casing; and friction means on the carrier and engaging the wall of the well casing for frictionally restraining the carrier from movement to permit said lug to be moved out of the short lateral portion of the J-slots, whereby the coupling element may be moved upwardly and the packing distorting member moved to distort the packing sleeve into sealing position and the gripping elements expanded to anchor the packer within the well casing.

7. A well packer including, a tubular mandrel having means for anchoring it within a well bore; a packing element carried by said mandrel; a coupling member having a flow passage therethrough and having means for connecting it in a well tubing string, said coupling member providing means for releasably coupling the mandrel to the well tubing; a housing formed in said coupling member for receiving a removable flow controlling device; a flow port through the wall of the coupling member above said housing for establishing communication between the flow passage and the exterior of the housing; and means carried by the coupling member for engaging and distorting the packing element into sealing engagement with the well bore, whereby flowing fluids are directed through the flow passage and port in the coupling member.
